Primary Examiner — Dana Meyrow

(74) Attorney, Agent, or Firm — Foundation Law Group;
Sevag Demirjian(57) CLAIM

The ornamental design for a hex bottle, as shown and described.

DESCRIPTION

FIG. 1—Top, front, left side perspective view of a hex bottle, showing my new design;

FIG. 2—Left side elevation view, the right side elevation view being a mirror image

FIG. 3—Rear elevation view; and,

FIG. 4—Top plan view.

The broken lines shown are included for the purpose of illustrating the unclaimed portions of the bottle and form no part of the claim.
